UNITED STATES PATENT OFFICE.

SIDNEY A. CROSS, OF NEW YORK, N. Y.

DESIGN FOR A PUZZLE-BOX.

SPECIFICATION forming part of Design No. 26,661, dated February 16, 1897.

Application filed January 2, 1897. Serial No. 617,844. Term of patent 31 years.

To all whom it may concern:

Be it known that I, SIDNEY A. CROSS, a citizen of the United States, residing at the city of New York, in the county of New York and State of New York, have invented and produced a new and original Design for Puzzle Boxes or Cases, of which the following is a specification, reference being had to the accompanying drawings, forming a part thereof.

10 In the drawings forming part of this specification the separate parts of my improvement are designated by the same numerals of reference throughout the several views, and in said drawings—

15 Figure 1 is a plan view of a puzzle box or casing, showing my design; and Fig. 2, a central transverse vertical section thereof on the line 2 2 of Fig. 1, these two views being necessary to fully illustrate my design.

20 The leading feature of my design consists in a raised hollow semispherical portion 5, which is secured to or formed on a circular base 6, and around which, at a predetermined distance therefrom, is formed or secured a

circular vertical flange or wall 7, which is 25 higher than the central raised hollow portion 8.

The central raised hollow portion 8 is circular in form in transverse section and is so formed as to represent a portion of a globe, 30 and formed in the apex or central upper portion thereof is a circular opening 9.

The base of the central hollow raised portion 8 is also a complete circle, and the space between said base and the vertical circular 35 wall or flange 7 is of equal width throughout, and the entire design is symmetrical in form and outline.

Having fully described my new and original design for a puzzle box or case, I claim as new 40 and desire to secure by Letters Patent—

The design for a puzzle box or casing herein shown and described.

SIDNEY A. CROSS.
